UNITED STATES PATENT OFFICE.

JOEL NILES WHEELER, OF GENEVA, ILLINOIS.

IRONING-TABLE.

1,177,667.

Specification of Letters Patent.

Patented Apr. 4, 1916.

Application filed July 3, 1915. Serial No. 37,865.

To all whom it may concern:

Be it known that I, JOEL NILES WHEELER, a citizen of the United States, and residing at Geneva, in the county of Kane and State of Illinois, have invented certain new and useful Improvements in Ironing-Tables, of which the following is a specification, reference being had to the accompanying drawings, forming a part thereof.

This invention relates to ironing tables having legs adapted to be folded under said table when the latter is not in use.

It has for its object to improve the general construction of tables of this nature, and in particular to provide an efficient and simple means for attaching the legs thereof so as to afford a stable structure, and one which can be manufactured at the minimum of cost.

In the drawings: Figure 1 is a side elevation of an ironing table embodying my invention. Fig. 2 is a view of the under side of the table, the legs being shown in a folded position. Figs. 3, 4 and 5 are detail views showing modifications in the form of construction of this invention.

Referring to the drawings, the numeral 1 designates the top of an ironing table, which is preferably of the usual form of ironing boards though other forms may be employed if desired. On the under face of the table top, near one end thereof, a transverse bar 2 is attached by means of screws or bolts 3, or other suitable fastenings. The outer ends of said bar are bent downward to form arms 4, as shown in the drawings, for the purpose of providing pivotal means for attaching a pair of supporting legs 5. Said legs are pivoted to the arms 4 by means of pins 6, and are rigidly connected to one another by means of the crossed brace rods 7 secured by means of the screws 8 to the legs. On the under side of said table top and adjacent the other end of the same, parallel guide-bars 9 are longitudinally disposed. Said guide-bars are formed of resilient material and are spaced apart substantially throughout their length and downward from the under side of said top to which they are secured by means of the screws 10 passing through holes provided in the upwardly and outwardly bent ends 11. A pair of legs 12, rigidly connected together in a manner similar to the pair 5, is slidably and pivotally connected to the under side of said top by means of the guide-bars.

A pair of links 13 is pivotally connected at one of their ends to the arms 4 by means of the pins 6, and at their other ends to the legs 12 at the points 14. A second pair of 60 links 13' have one of their ends pivoted to the legs 5 at the points 15 and their other ends pivoted to the legs 12 at the points 16.

A rod 17 connects the upper ends of the legs 12 and is adapted for sliding engagement with the under faces of the guide-bars throughout their length, the said ends being positioned adjacent the outer edges of said guide-bars. The sliding engagement of the rod with the guide-bars causes the ends of 70 the pair of legs 12 to be held in frictional engagement with the under face of the table-top and the longitudinal movement of said ends is limited by the bent ends 11 of the guide-bars. The pair of legs 5 is spaced 75 apart a sufficient distance to permit them to embrace the lower ends of the other pair of legs when they are both folded beneath the table, as shown in Fig. 2. By reason of the action of the connecting links both pairs of 80 legs can be folded together or opened out by one operation, the upper ends of the pair of legs 12 being pivoted and slidable along the under face of the table by means of the guide-bars, as described.

In order to hold the legs 12 in a more secure or firm position when the table is in use a spring-catch 21 having a depending portion 22 is secured to the under face of the table between the guide bars 9. The depending end is adapted to engage with the rod 17 connecting the ends of the legs 12 and hold same against the ends of the guide bars.

It is evident that modifications in the details of construction of this invention may be made without departing from the spirit hereof, and which would be included in the appended claim. The guide-bars 9 could be made in other forms, as shown in Figs. 100 3 and 4 of the drawings, and said bars could be attached to the table top by the use of wooden blocks and bolts as shown in Fig. 4. The same control of the upper ends of the pair of legs 12 could be accomplished by the 105 use of a single guide-bar and attaching guides of metal 20, or other suitable material, to the rod 17, as illustrated in Fig. 5.

From the description it will be apparent that the strength of this ironing table is materially increased by the addition of the guide-bars on its under face, while the said

guide-bars provide a cheap and efficient means for operation of the parts and for controlling the positions of the supporting legs.

5 Having thus described my invention, what I claim as new and desire to secure by Letters Patent is:

An ironing table comprising in combination, a top, a pair of legs pivotally secured 10 to the under surface of said top adjacent one end thereof, resilient guide-bars disposed on said under surface adjacent the other end thereof, said guide-bars being spaced apart from said surface throughout their

length and provided with upwardly and outwardly extending ends, another pair of legs connected by links with the first mentioned pair of legs whereby the upper ends of both pairs of legs will be inclined toward one another when the latter are folded out, 20 a rod disposed between the second pair of legs and at a distance from their upper ends whereby frictional engagement between said rod and said guide-bars will permit sliding and pivotal movement of the said ends on 25 the under surface of the top when the table is erected.

J. NILES WHEELER.
